UNITED STATES PATENT OFFICE

JESSE G. KING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed May 30, 1929. Serial No. 367,165.

This invention relates to refrigerating apparatus and more particularly to the arrangement and support of various elements in the compressor condenser receiver type of refrigerant supply unit.

One of the objects of the invention is to conveniently locate and support the receiver so that it may be easily removed or replaced without disconnecting the refrigerant lines. 10 Another object is to conveniently support a switch so that it may be easily adjusted or removed if necessary.

Further objects and advantages of the present invention will be apparent from the 15 following description, reference being had to the accompanying drawings, wherein a preferred form of the invention is clearly shown.

In the drawings:
20 Fig. 1 is a top view of a preferred arrangement of a refrigeration liquefying unit;
Fig. 2 is an end view of the apparatus of Fig. 1;
Fig. 3 is a top view of one of the receiver 25 ports separated from its supporting bracket; and

Fig. 4 is a side view of Fig. 3 with part of the bracket broken away to show the depressed part of the slot.

30 In the arrangement of apparatus manufactured in large quantities there is not only the problem of placing the elements in their best position of operation but also the problem of assembling the essential parts with as 35 few additional elements as possible. Where large quantities of a particular form of apparatus are assembled even one or two unnecessary parts means a big saving over a period of time. Furthermore the more quickly 40 the apparatus is assembled the more saving there is in labor cost. Accordingly it is one of the objects of this invention to have refrigerating apparatus that may be easily and quickly assembled, and also one in which 45 there are certain parts thereof that may be disassembled without shutting off the refrigerant lines.

In Fig. 1 there is disclosed the preferred 50 form of arrangement of a refrigerant liquefying unit. A platform 10 is resiliently

mounted upon the rubber rollers 11. A compressor 12 receives the evaporated refrigerant in its crankcase and after compressing it discharges the compressed gas through the conduit 13 to the condenser 14. From the condenser 14 the now liquefied refrigerant passes through a conduit 15 to the inlet port 16 of the receiver 17. This inlet port is more particularly described later on. From the receiver the refrigerant passes up through 55 the upper port 18 and conduit 19 to a cooling unit of any shape or form. It is preferred, however, to use a flooded float controlled type of evaporator such as disclosed in the patent to R. G. Osborn 1,556,708 issued 60 Oct. 13, 1925. From such a cooling unit the evaporated refrigerant returns to the crankcase of the compressor 12 thru the conduit 47. The compressor is run by the motor 20 having the motor pulley 21 connected by the 65 belt 22 to the compressor pulley 23. A fan 24 is preferably located on the motor pulley shaft 25. Likewise fan blades may be located on the compressor pulley between the center and periphery thereof for cooling the 70 condenser and the casings of the other apparatus. It will be noted that the condenser is conveniently located between the compressor and the fan blades of the compressor pulley. An automatic pressure responsive 75 switch 26 is connected by the electrical connection 27 to the power mains connected to the motor 20. This switch is preferably of the type disclosed in the copending application of Otto M. Summers, S. N. 281,599, filed May 29, 1928 and is connected in the 80 system as disclosed in that application. As the system is a closed one the pressure of the gas in the return conduit 47 is directly related to the temperature of the cooling 85 unit. The switch has the control means 28 by which the pressure and hence the temperature at which the switch will operate may be manually set according to the desires of the person utilizing the apparatus. 90

A preferred arrangement of the receiver and switch is disclosed in the drawings. The receiver is spaced from the platform and preferably located slightly to one side of it. This receiver is supported in this spaced 95 100

position by means of one or more brackets. While one long bracket could be used it is preferable to use two brackets 29 and 30. These brackets have one end 31 attached preferably by welding to the underside of the platform and having an off set portion 32 substantially parallel to the plane of the platform at a short distance above it. This portion 32 is slotted at 33 and at the center of the slot has a depressed portion 34. The tank 17 has the two ports previously mentioned for the inlet and outlet of the refrigerant. These ports in their preferred form comprise an integral upstanding boss 35 with screw threads on its outer periphery surface. Two washers 36 are placed upon this port and then a nut 37. This port can then be attached to the bracket by inserting the boss in the slots 33 with the washers above and below the depressed portion 34. The nut 37 is then screwed down into locked engagement. By this means the receiver is supported by its ports and no additional supporting elements are necessary. Each of these ports has preferably a valve between it and the conduit to which it is connected. The gas in such a valve passes up a short shank 38 and makes a right angle bend through the elbow 39. A continuation 40 of the shank 38 has a shut off valve located therein which can be reached in the apparatus disclosed by removing the cap 41. The receiver can be assembled or disassembled from the bracket without shutting off the refrigerant lines and disconnecting the conduits from the rest of the refrigerant apparatus. All that is necessary is to unscrew the nut 37 and to pull the receiver out of the slots 33. As the receiver is located in the front of the apparatus when it is placed in the machine compartment of the refrigerating cabinet it is very convenient to locate the automatic switch 26 upon these brackets also. For this purpose holes 42 are drilled in the bracket and the switch is mounted on the bracket by the bolts 43. As the switch uses two holes in the left hand bracket and one in the right hand bracket of Fig. 1 each bracket is punched with two holes on its right hand side and one hole on its left hand side so that the brackets may be interchangeable in either of the two positions. This switch 26 may likewise be removed from the supporting bracket without disconnecting the electrical connection 27 to the motor 20.

Accordingly there has been disclosed a very convenient and economical method of supporting the receiver and automatic switch from the platform of a refrigerant liquefying unit. This method of support not only adds to the convenience in assembling and disassembling the apparatus but likewise results in fewer fastening means being used.

While the form of embodiment of the invention as herein disclosed constitutes a preferred form, it is to be understood that other

forms might be adopted, all coming within the scope of the claims which follow.

What is claimed is as follows:

1. In combination, a platform adapted to support a refrigerant liquefying unit, a receiver spaced from said platform, a plurality of brackets attached to said platform, said brackets being slotted, an inlet means and an outlet means for the liquefied refrigerant on said receiver, said means adapted to be inserted in said slots and to thereby support said receiver in said spaced relation. 70

2. A receiver for refrigerant comprising a tank, an inlet and outlet means on said tank, said means being screw-threaded, fastening means on said means and a bracket to which the inlet and outlet means are adapted to be removably secured. 80

3. In combination, a platform for supporting a portion of a refrigerating system, a bracket attached to said platform, a receiver having inlet and outlet means, and means on one of said last mentioned means for connecting the receiver to the bracket. 85

4. In combination, a support, a bracket attached to the support, a tank member having inlet and outlet pipe connections, and a pair of nuts threaded upon one of said connections for fastening the tank member to the bracket. 90

In testimony whereof I hereto affix my signature. 95
